UNITED STATES PATENT OFFICE.

HERBERT L. NORRIS, OF PROVIDENCE, RHODE ISLAND.

DESIGN FOR A BADGE-PIN.

SPECIFICATION forming part of Design No. 22,638, dated July 18, 1893.

Application filed October 5, 1892, Serial No. 447,964. Term of patent 7 years.

To all whom it may concern:

Be it known that I, HERBERT L. NORRIS, a citizen of the United States, residing at Providence, in the State of Rhode Island, have invented and produced a new and original Design for a Badge-Pin, of which the following is a specification, reference being had to the accompanying drawings, forming part thereof.

Figure 1, represents the face view of a badge pin embodying my design, and Fig. 2, represents a top edge view of the badge pin.

The leading feature of my design consists in an ornamental plate provided with two parallel rectangular openings extending transversely of the plate, and a raised rectangular surface extending from one of the said openings to the other, and also with a circular pendant having upon its face a pictorial representation in relief within a circular border.

In the drawings, A is the ornamental face plate of the pin, provided with the parallel rectangular openings b, b, and with the raised rectangular surface C, occupying the intervening space between the said openings, and to the said plate, A is attached, the circular pendant B, having upon its face a pictorial representation in relief D, inclosed by a circular border, e.

What I claim is—

The design for a badge pin, herein shown and described.

HERBERT L. NORRIS.

Witnesses:

SOCRATES SCHOLFIELD,
HENRY J. GEER.
